UNITED STATES PATENT OFFICE.

PERRY T. COONS, OF MONTCLAIR, NEW JERSEY, ASSIGNOR TO THE AMERICAN STEEL
AND WIRE COMPANY OF NEW JERSEY, A CORPORATION OF NEW JERSEY.

WIRE FABRIC.

Application filed May 5, 1926. Serial No. 106,908.

This invention relates to wire fabric and more particularly to a paper-backed wire fabric usable as a reinforcement and support for plastic material such as plaster, stucco, cement, concrete, and the like.

One object is to provide a fabric of this class which will have all the wires thereof welded together so as to provide a relatively rigid and strong material.

10 Another object is to provide a fabric of this class having two sets of wires arranged to form a mesh and welded together, said wires being on the material receiving side of the backing sheet and being adapted to be embedded in the plastic material to form a reinforcement.

20 A further object is to provide a fabric of the class described having the novel construction, design, and combination of parts hereinafter described and illustrated in the accompanying drawings.

In the drawings:

Fig. 1 is a plan of a section of fabric constructed in accordance with this invention, and

25 Fig. 2 is a sectional view of the fabric.

Referring more particularly to the drawings, the numeral 2 designates the foundation or backing sheet for the fabric which may be composed of any flexible material, but is preferably composed of paper or other fibrous material. A wire netting composed of two sets of wires 3 and 4 arranged at right angles is mounted along the face side of the sheet 2. 35 The inner set of wires 3 are located against the face of the backing sheet 2 for their entire length, and the second set of wires 4 which extend at right angles to the first set of wires 3, are located outside of and overlie the first set of wires 3, and are welded to said first set of wires at the points of intersection 40 of said wires.

45 A plurality of single wires 6 are arranged along the back side of said backing sheet 2 and extend parallel to the second set of wires 4, and at right angles to the first set of wires 3 so as to cross the wires 3.

50 The foundation or backing sheet 2 is provided with apertures 7 opposite the points of intersection or crossing of the wires 3 and 6, and the wires 3 and 6 are welded together at

their points of intersection 8, so as to form a composite structure.

The wires 6 serve to hold the backing or foundation sheet in position, and to stiffen 55 and reinforce the entire structure.

The welding together of all the wires 3, 4 and 6 provides an integral and rigid construction not obtainable by twisting or otherwise mechanically tying the wires together. 60

Another feature of the fabric of this invention is that it provides a reinforced mesh or netting composed of the wires 3 and 4, which is entirely embedded in the plastic material, thereby reinforcing it both vertically and horizontally. 65

While I have shown and described one specific embodiment of my invention, it will be understood that I do not wish to be limited thereto, since modifications may be made 70 without departing from the scope of my invention as defined in the appended claim.

I claim—

The combination with a foundation sheet of relatively thin flexible material, of a wire 75 netting on one face of the sheet comprising a first set of straight wires located against the face of the sheet for their entire length and a second set of straight wires extending at right angles and located outside of the 80 first set of straight wires and flash welded thereto at their points of intersection, and single straight wires on the opposite face of said foundation sheet and extending parallel to said second set of wires of said netting 85 and spaced between the wires of said second set, said single wires crossing the wires of said first set of wires of the netting, and said sheet of flexible material being provided with apertures opposite the points of crossing of 90 said single wires and the wires of said first set of wires of the netting, said apertures being of such size as to permit said sheet to move relative to said wires and to flex sufficiently to permit said straight wires to engage without bending, and said single wires and the wires of said first set of wires of said netting being flash welded together at the crossing points thereof. 95

In testimony whereof, I have hereunto 100 signed my name.

PERRY T. COONS.
